UNITED STATES PATENT OFFICE.

SERVATINS HEIMERMAN, OF CHILTON, WISCONSIN.

CHIMNEY CLEANER.

Application filed September 22, 1922. Serial No. 589,891.

To all whom it may concern:

Be it known that I, SERVATINS HEIMERMAN, a citizen of the United States, residing at Chilton, in the county of Calumet and State of Wisconsin, have invented certain new and useful Improvements in a Chimney Cleaner, of which the following is a specification.

This invention relates to a chimney cleaner and has for its principal object to provide a device whereby the soot which may collect within the interior of a chimney may be easily cleaned with a simple and efficient apparatus.

Another object of the invention is to provide a chimney cleaner of the above mentioned character which can be easily placed upon a chimney and arranged adjacent the top of the same so as to allow the chimney cleaner to be descended or lowered into the chimney whereby the soot collected on the inner walls of the chimney may be cleaned.

A still further object of the invention is to provide a chimney cleaner of the above mentioned character which is simple in construction, inexpensive in manufacture, strong and durable.

Other objects and advantages of the invention will become apparent during the course of the following description.

In the drawings, wherein like numerals designate like parts throughout the same,

Figure 1 is a front elevation of the invention showing the chimney cleaner applied to a chimney.

Figure 2 is a side elevation, and

Figure 3 is a central vertical section of the tubular holder showing the arrangement of the cleaning brush and the weight associated therewith and supported within the upper portion of the tubular holder.

In the drawings, wherein for the purpose of illustration is shown the preferred embodiment of my invention, the numeral 1 designates the frame forming a part of my invention, and the frame is provided with a pair of vertically extending tubular members 2 which are so arranged with relation to the frame 1 as to form a longitudinal cut out portion between the two respective tubular members. These tubular members 2 are adapted to receive the ends 3 of an auxiliary frame 3' which is associated with the main frame 1 and this auxiliary frame 3' can be adjusted with relation to the main frame by means of allowing the ends 3 there-

of to be slidably moved within the tubular members 2. The auxiliary frame is held in adjusted position with relation to the main frame by the set screws 4. The main frame 1 is secured to the chimney 5 adjacent the upper edge thereof by means of suitable clamping members 6.

Pivottally mounted in the longitudinal cut out portion formed in the frame 1 and between the tubular members 2, is a tubular member 7. This tubular member 7 is threaded at its upper end to receive and support thereon an enlarged funnel shaped head 8. This is more clearly shown in Fig. 70 of the drawings. This funnel shaped head 8 will normally be positioned in the enlarged opening 9 formed at the upper portion of the frame 1 and within the auxiliary frame 3'. The tubular member 7 is pivotally mounted in the frame 1 by means of a yoke 10 and the outwardly projecting pins 11 which extend through the tubular members 2 on the main frame in such a manner so as to allow the tubular member 7 to freely swing from without the frame 1 when it is desired to use the chimney cleaner to be hereinafter fully described.

Adapted to seat within the enlarged funnel shaped head 8 of the tubular member 7 is an egg shaped weight, and this weight consists of two sections, an upper section 12 and a lower section 13. These sections 12 and 13 which form the weight are held together by means of a suitable bolt which passes centrally therethrough and said bolt 14 has a nut 15 threaded on one end thereof so as to allow the two sections 12 and 13 to be firmly held in engagement with each other and to prevent any play between the two sections. The upper section 12 of the weight is provided with recesses over its entire outer face for the purpose of receiving the bristles 17 whereby the section 12 will act as a brush member when in use. The opposite end of the bolt 14 is provided with an eye 18 and this eye is arranged below the bottom of the bottom section 13 of the weight and is adapted to receive one end of a cable 19 and this cable 19 extends through the tubular body 7. To further guide the cable 19 a sleeve 20 is threaded upon the lower end of the tubular member 7 and carried by this sleeve 20 is the pulley 21. Directly below this pulley 21 and secured on the frame 1 is a similar pulley 22. The purpose of these two pulleys 21 and 22 is to

allow the cable 19 to be easily guided over the two pulleys and the opposite end of the cable 19 is held or secured to any suitable place. When the cable 19 is drawn tightly 5 back within the tubular member 7 and is secured at its free end, the weight and the bristles 17 carried thereby will be caused to seat within the enlarged funnel shaped portion 8.

10 A spring element 23 is provided upon the frame 1 and adjacent the cut out portion formed between the two tubular members 2, and the pivotal connection of the tubular member 7 with the frame 1, and this spring 15 element 23 has an angular extending arm 24. The function of this spring element 23 and the angular extending arm 24 carried thereby is to cause the tubular member 7 to be released from its normal position whereby 20 the funnel shaped portion 8 carried by the tubular member 7 will be caused to communicate with the interior of the chimney 5 so as to permit the weight and the brush element associated therewith to easily descend within 25 the chimney. Extending across the frame 1 and carried thereby is another spring element 25. This spring element 25 is arranged on the frame 1 adjacent the upper edge of the chimney 5 and extends outwardly from 30 the frame 1. The purpose of this spring element 25 is to allow and to further keep the tubular member 7 and the funnel shaped member carried thereby in communication with the interior passage of the chimney 5, 35 and will prevent the tubular member 7 and the weight carried in the funnel shaped portion 8 from swinging out of communication with the interior of the chimney as more clearly shown in Fig. 2 in the dotted lines.

40 Normally the tubular member 7 together with the weight and the bristles 17 carried thereby and which is supported in the funnel shaped head 8 of the tubular shaped member 7 is positioned in the longitudinal 45 cut out portion formed between the two tubular members 2 and the enlarged cut out portion 3 in the auxiliary frame 3' in such a manner that the tubular member 7 will lie against the arm 24 of the spring 23 and by 50 having the cable 19 which extends longitudinally through the tubular member 7, secured at one end to the brush and weight drawn tightly, the spring element 23 will be caused to become tensioned. By releasing 55 the cable 19 from its secured position the spring element 23 will have a tendency to force the tubular member 7 out of the frame 1 and into engagement with the interior passage of the chimney 5. After the tubular 60 member 7 is swung to the position as shown in the dotted lines in Fig. 2 of the drawings, the weight sections 12 and 13 will then cause the bristles 17 carried by the top section 12 of the weight to descend into the interior of 65 the chimney 5 and thoroughly clean the

walls thereof of any soot or other material which may collect thereon.

To retract the weight and the brush element associated therewith, the cable 19 is pulled or drawn until the weight is caused to seat within the enlarged funnel shaped head 8 of the tubular member 7 and by further pulling on the cable 19 the tubular member 7 hinging on its pivotal connection 11 within the frame 1 will be caused to again 75 assume its upright position. A suitable lightning rod 26 may be associated with the frame and the chimney 1 and can be mounted adjacent one of the tubular members 2 by means of the spacing element 27 for the purpose well known.

It will thus be seen from the foregoing description and operation, that a chimney cleaner has been provided which is simple in its construction, easily operated and does 85 not interfere with the chimney in any respect. It is to be further understood that the form herewith shown and described is to be taken as a preferred embodiment of the same, and that various changes in the shape, 90 size and arrangement of parts may be resorted to without departing from the spirit of the invention or the scope of the subjoined claims.

Having thus described my invention, what 95 I claim is:

1. The combination with a chimney, of a frame associated adjacent the upper end therewith, a tubular member pivotally mounted in the said frame, said tubular member having an enlarged head, a cleaning element seated in the said enlarged head, means associated with the frame for causing the tubular member to communicate with the interior of the chimney, and means associated with said cleaning element to allow the same to descend into the chimney, and means for withdrawing the cleaning element therefrom.

2. The combination with a chimney, of a frame associated adjacent the upper end therewith, a tubular member pivotally mounted in the said frame, said tubular member provided with a funnel shaped head at its upper end, a weight seated in the said funnel shaped head, a cleaning element carried by the said weight on the top face thereof, a cable fastened to the weight and extending through the tubular member for holding the weight and cleaning element in its seated position and also allow the brush to be lowered into the chimney, a spring mounted on the said frame for causing the tubular member and cleaning element to swing into communication with the interior of the chimney, and means on the said frame for holding the tubular member in communication with the interior of the chimney.

3. The combination with a chimney, of a frame associated therewith and adjacent the

upper end thereof, a tubular member pivotally supported in the said frame, said tubular member provided with a funnel shaped head at its upper end, a weight seated in the said head, a cleaning element carried by the said weight on the top face thereof, a cable fastened to the weight and extending through the tubular member for holding the weight and brush in its seated position, and also allowing the brush to be lowered in the chimney and withdrawn therefrom, guide pulleys associated with the tubular member and the frame for receiving the said cable, a

spring mounted on the said frame for causing the tubular member and cleaning element to swing into communication with the interior of the chimney, and means on the said frame for holding the tubular member in communication with the interior of the chimney.

In testimony whereof I affix my signature in presence of two witnesses.

SERVATINS HEIMERMAN.
